FANT ROBERTS, OF ELDORADO, KANSAS.

PUMP.

1,399,402.

Specification of Letters Patent.

Patented Dec. 6, 1921.

Application filed July 15, 1920. Serial No. 396,442.

To all whom it may concern:

Be it known that I, FANT ROBERTS, a citizen of the United States, and a resident of Eldorado, in the county of Butler and State 5 of Kansas, have invented certain new and useful Improvements in Pumps, of which the following is a specification.

My invention is an improvement in pumps, and has for its object to provide a pump especially adapted for use with oil wells for pumping oil, wherein the pump has a double barrel and a double plunger, together with valves arranged to permit the plungers to function simultaneously to lift the oil.

15 In the drawings,

Figures 1 and 2 show the improved pump in longitudinal section.

In the present embodiment of the invention, an upper barrel 1 is provided, and a 20 lower barrel 2, the upper barrel being of greater diameter than the lower barrel, and the upper end of the lower barrel is connected to the lower end of the upper barrel in any suitable or desired manner. An 25 upper plunger 3 is arranged within the upper barrel, and a lower plunger 4 is arranged within the lower barrel. These plungers are hollow, cylindrical bodies, as shown, and they have packing washers 5 and packing 30 rings 6, which insure a tight fit between the barrel and the plunger.

At the upper end of the upper plunger, there is arranged a valve crown, or cage 7, in which is mounted a ball valve 8, and this 35 valve coöperates with a reversible seat 9, which is held at the upper end of the plunger, between the crown and a bushing 10, the bushing being connected to the crown at one end, and to a union 11 at the other, which 40 connects the bushing with the upper end of the plunger 3. This bushing 10, as shown, has an annular rib, which is arranged between the abutting ends of the crown 7 and the union 11.

45 The packings and packing rings are held on the plungers by nuts 12 and lock nuts 13, and the plungers are connected by a section 14 of piping, which connects at its ends with the plungers, forming a continuous passage through the plungers. This section 14 of pipe is connected to the lower plunger by means of a union 15, and this union is a 50 valve cage or crown. The upper end of the

lower plunger is a seat with which a ball valve 16 in the cage or crown coöperates. 55

The lower barrel 2 is connected at its lower end by a union 17 with a pipe or casing 18 which has a transverse partition 19. Above the partition, the wall of the casing is perforated, while below the partition it is im- 60 perforated, and the lower end of this casing 18 fits into the enlarged end of a union 20. The enlarged lower end of this union is en- 65 gaged by a similar casing 21, having the partition 22 with the perforated wall above and imperforated wall below.

Valve casings 22 are arranged within the lower end of the barrel 2, the union 20, and a union 23 similar to the union 20 and connected with the lower end of the casing 21, 70 all of these valve bodies 22 being alike, and each consisting of the body, a crown or cage 24, and a ball valve 25. Each valve body as shown has packing rings, and the ball valve coöperates with the upper end of the body 75 as a seat.

A casing 26, similar to the casings 18 and 21, is connected with the lower end of the union 23. Pipes 27 and 28 extend longitudinally of the barrels, at opposite sides thereof, 80 and each of the said pipes 27 and 28 communicates with the barrel 1 at its upper end, as clearly shown at 29 in Fig. 1, by means of an elbow or the like.

The pipe 29 has a T 30 interposed in its 85 length, and the lateral branch of the T communicates with the barrel 1 just below the upper plunger. A stuffing box 31 is arranged at the upper end of the connecting pipe 14 which connects the plungers, between the 90 said pipe and the barrel 2, and the T 30 connects with the barrel between the stuffing box and the upper plunger.

The pipe 28 has a T 32 in its length, whose lateral branch communicates with the barrel 2 just below the stuffing box 31. This stuff- 95 ing box consists of the usual packing, and the retaining rings at the ends, the said rings being beveled in the usual manner. The lower end of the pipe 27 communicates 100 with the casing 18 below the partition 19, the arrangement being such that the uppermost valve 25 is above this communication. The pipe 28 connects at its lower end with the casing 21 below the partition 22, and the 105 arrangement here is such that the intermedi-

ate valve 25 is above such communication and between the same and the communication of the pipe 27, while the lowermost valve is below the said communication.

5 The operation of the device is as follows:—

Suitable operating mechanism being connected with the uppermost plunger, when the said plunger is drawn upward, the lower plunger, of course, moving therewith, liquid 10 will be drawn into the lower end of the lower barrel by the lower plunger, the liquid passing by way of the casing 18 and past the upper valve 25 into the lower barrel. Liquid will also be drawn into the upper barrel 15 above the stuffing box 31 by the upper plunger, the liquid passing by way of the casing 21, the intermediate valve 25, the pipe 27, and the T 30.

Check valves 33 of usual construction are 20 interposed in the length of the pipes 27 and 28. A check valve is arranged on each side of each T 30 and 32. These check valves are arranged to permit the free, upward flow 25 of the liquid but to prevent the downward flow of the liquid. On the downward stroke of the pump, liquid is drawn into the lower barrel above the lower plunger 4 through the casing 26, the lowermost valves 25, the pipe 28 and the T 32, the check 33 below 30 the T 32 preventing the return of the liquid. That liquid which is below the upper plunger is forced out through the T 30 and the pipe 27 to the barrel 1 above the plunger 3, the check valve above the T 30 preventing 35 the return of the liquid, and that check valve 33 below the T preventing the passage of the liquid downward. That liquid which is below the lower plunger is forced out past the check 16 and through 40 the pipe 13 and the upper plunger and past the check 8 to the upper portion of the barrel 1.

The downward movement of the upper plunger assists in the circulation of the liquid 45 from below the plungers to above the plungers. Thus on each stroke of the pump in both directions there is a movement of liquid by both plungers.

I claim:—

50 1. A pump comprising upper and lower connected barrels, a plunger in each barrel, said plungers being hollow, a hollow connection between the plungers, a stuffing box between the plungers through which the connection moves, check valves in connection with the plungers for permitting the free, upward movement of the liquid and for preventing the downward movement, a plurality of connections between the upper barrel 55 above the upper plunger and the lower barrel below the lower plunger, each of said connections connecting intermediate its ends with one of the barrels, one of the connections being above the stuffing box and the 60 other below the said box, check valves in

each of the said connections above and below the communication with the barrels, the said connections at their communication with the lower barrel being offset with respect to each other, a check valve below each of the 70 said communications, and a check valve between the uppermost of the said communications and the lower plunger, said valves being arranged to permit the free, upward flow of the liquid and to prevent the downward flow. 75

2. A pump comprising a casing, a plurality of double acting plungers rigidly connected and ported to permit the free flow of liquid from below the lower plunger to 80 above the upper plunger, check valves for preventing the downward flow of the liquid through the plungers, a stuffing box in the casing between the plungers, a plurality of by-passes in connection with the casing and 85 connecting that part of the casing above the upper plunger with that part of the casing below the lower plunger, and communicating with the casing intermediate the ends of the by-passes and between the plungers, 90 and check valves for constraining the liquid to flow upwardly through the by-passes, the connection of the by-passes with the casing below the lower plunger being offset longitudinally of the casing with respect to each 95 other, and check valves below the said connections of the by-passes and above the uppermost connection.

3. A pump comprising a casing, a plurality of double acting plungers rigidly connected and ported to permit the free flow of liquid from below the lower plunger to 100 above the upper plunger, check valves for preventing the downward flow of the liquid through the plungers, a stuffing box in the 105 casing between the plungers, a plurality of by-passes in connection with the casing and connecting that part of the casing above the upper plunger with that part of the casing below the lower plunger, and communicating 110 with the casing intermediate the ends of the by-passes and between the plungers, and check valves for constraining the liquid to flow upwardly through the by-passes. 115

4. A pump comprising a casing, a pair of rigidly connected double acting plungers in the casing and ported to permit the free flow of liquid from below the lower plunger to 120 above the upper plunger, and having check valves for preventing the downward flow, by-passes connecting that portion of the casing below the lower plunger with that portion of the casing above the upper plunger and communicating with the space 125 between the plungers, a stuffing box between the plungers and check valves in the by-passes above and below said connection between the plungers for constraining the liquid to flow upwardly. 130

5. A pump comprising upper and lower connected barrels, a plunger in each barrel, a connection between the plungers, a stuffing box between the plungers through which the connection moves, a plurality of connections between the upper barrel above the upper plunger and the lower barrel below the lower plunger, each of said connections connecting intermediate the ends with one of the barrels, one of the connections being above the stuffing box and the other below the said box, and check valves for constraining the liquid to flow upward.
- 10 6. A pump comprising upper and lower connected barrels, a plunger in each barrel, said plungers being connected, a plurality of
- connections between the upper barrel above the upper plunger and the lower barrel below the lower plunger, each of said connections connecting intermediate its ends with 20 one of the barrels, said connections at their communication with the lower barrel being offset with respect to each other, an imperforate partition between the offset points of communications of the connections of said 25 connections with the lower barrel and an imperforate partition between the point of communication with the upper of said connections and the lower barrel and the lower plunger, and check valves for constraining 30 the liquid to flow upward.
